UNITED STATES PATENT OFFICE.

DANIEL L. DODGE, OF INWOOD, AND THOMAS F. ARMSTRONG, OF FAR ROCKAWAY,
NEW YORK.

DRIVING AND REVERSING MECHANISM.

1,167,984.

Specification of Letters Patent. Patented Jan. 11, 1916.

Application filed December 11, 1914. Serial No. 876,655.

To all whom it may concern:

Be it known that we, DANIEL L. DODGE and THOMAS F. ARMSTRONG, citizens of the United States, and residents, respectively, of 5 Inwood, in the county of Nassau and State of New York, and of Far Rockaway, in the county of Queens, in said State, have jointly invented a certain new and useful Improvement in Driving and Reversing Mechanism, 10 of which the following is a full, clear, and exact description, reference being had to the accompanying drawings, forming part of this specification.

The invention relates to driving and reversing mechanism which comprises shiftable parts and means to enable them easily to be shifted, the main object of the invention being to produce an especially desirable connection for the driving-shaft and propeller-shaft of a motor-boat.

The invention consists of the driving and reversing mechanism which is hereinafter described and specified in the claims.

On the accompanying two sheets of drawings, on which like reference-numerals designate like parts of different views, Figure 1 is a broken side-elevation of this mechanism; Fig. 2, a sectional plan thereof; and Fig. 3, a plan of some parts and diagrammatic representation of others, illustrating the reversing operation.

The mechanism is shown mounted on the base 1 and the five posts 2, 3, 4, 5 and 6 formed thereon, the driving shaft 7 being supported by the post 2, and the driven shaft 8 by the posts 3 and 4. But this base and the posts 2, 3 and 4 will not be required in a boat in which the motor-shaft and propeller-shaft, represented by shafts 7 and 8, 40 are supported by other means.

The axes of the shafts 7 and 8 are on a straight line, the rear end of the former or motor-shaft being near the front end of the other or propeller-shaft. The wheel 9, 45 which is a bevel-wheel, preferably of metal, comprises the hub 10 and working surface 11 and is affixed to the shaft 7 by means of the key 12 and screw 13, the hub being close to the post 2. The central portion of this 50 wheel forms a clutch-member in which is the conicofrustum-shaped cavity 14. The wheel 15 is also a bevel-wheel, preferably also of metal. It has the working surface 16, and is affixed to the shaft 8 close to the 55 post 3 by the key 17 and screw 18. The

sleeve 19, disk 20, and ring 21, which are fast together, form a conicofrustum-shaped clutch-member which is shiftable from and into engagement with the clutch-member that is part of the wheel 9. The ring 21 is 60 fastened to the disk by screws 22 and is preferably made of wood. The disk and ring are fast on the sleeve which is loose on the shaft 8 but prevented from turning independently by the feather 23. The collars 24 65 and 25 are fast on the sleeve 19 and the shiftable clutch-member is normally kept engaged with the other by the pressure of the coil-spring 26 surrounding the shaft 8 and bearing at one end against the collar 70 25 and at the other against the post 4, so that if the driving shaft then turns the clutch and shaft 8 will turn with it as though they were all a single shaft.

The transverse wheel 27, which is preferably made of wood, has the working bevel-surface 28 and is mounted on the stud 29 which fits tightly in the post 5 and is fastened thereto by suitable means, such as the pin 30. This stud extends loosely through 80 the sleeve 31, which passes through and is tight in the wheel and on which are the collars 32 and 33 and the disk 34, these being fast on the sleeve, and the wheel is attached to the disk 34 by the bolts 35. This wheel is 85 shiftable axially from the position in which it is shown in Fig. 2 so that its working surface 28 will make firm contact with the working surfaces 11 and 16 of the two other bevel-wheels. The surfaces 11, 16 and 28, 90 as well as the coacting surfaces of the clutch, are preferably friction-surfaces.

The mechanism for shifting the wheel 27, and the clutch-member which is mounted on the shaft 8, comprises the two angular shifting-levers 36 and 37, and the upright lever which is to be described and which is movable by hand to actuate the two other levers. These angular levers are mounted on the post 6 and on the screw-studs 38 and 39 100 which extend through the levers and into the post. The lever 36 comprises the flat slotted arm 40, and the branches 41 which form its other arm and on which are rollers 42 which fit loosely between the collars 24 105 and 25, on opposite sides of the sleeve 19, and the lever 37 comprises the flat slotted arm 43 and the branches 44 which form its other arm and on which are rollers 45 which fit loosely between the collars 32 and 110

33, on opposite sides of the sleeve 31. The arms 40 and 43 are close together, one being above the other, and the upright lever 46, next to its lower end where it is round, 5 extends through them, fitting loosely in the slots 47 and 48 in the arms 40 and 43, respectively. The upright lever is mounted on the screw-stud 49 projecting from the arm 50 fastened to the post 4 by the screws 15 51, but obviously this lever might be otherwise supported.

When the clutch-members are engaged, as they are shown in Fig. 2, the wheel 27 is kept out of contact with the wheels 9 and 15 by force exerted by the spring 26 on the sleeve 31 through the levers of the shifting-mechanism. If the lever 46 is moved by hand so that it travels in the slots 47 and 48 toward their inner ends, the shiftable 20 clutch-member will be drawn from the wheel 9 and simultaneously the transverse wheel will be drawn toward the other wheels, and should the hand be removed from the lever 46, immediately thereafter the parts will be 25 restored by the spring 26 to the positions in which they are shown in Fig. 2. It is plain, therefore, that by moving the lever 46 to the proper position and then holding it there the shiftable clutch-member may be disconnected from the wheel 9 and this wheel be caused to act on the shaft 8 through the transverse wheel 27 and the wheel 15, as indicated by Fig. 3, so as to reverse the action 30 of the driving shaft on the driven shaft, and that when the lever 46 is released the driving shaft will instantly become operative to turn the driven shaft in the direction of its own motion. The lever 46 may also be moved and held so that no motion 35 will be imparted to the driven shaft, from the driving shaft.

It will be understood that the principle of the invention does not depend on all of the described details of construction of the 45 mechanism shown, and will not be affected by various changes which may be made therein.

Having thus described our invention, what we claim as new and desire to secure by Letters Patent, is:

1. In driving and reversing mechanism the combination of a driving shaft, a driven shaft the axis of which is a prolongation of that of the driving shaft and one end of 55 which faces and is adjacent to an end of the driving shaft, a driving bevel-wheel fast on one shaft, a driven bevel-wheel fast on the other shaft, a transverse axially shiftable bevel-wheel, a shiftable clutch-member mounted on one shaft adjacent to the wheel which is on the other shaft and which includes a coacting clutch-member, the shiftable clutch-member being movable axially to and from said coacting clutch-member, 60 and shifting mechanism connected both to

said shiftable clutch-member and to the transverse bevel-wheel and operative to shift them simultaneously as described.

2. In driving and reversing mechanism the combination of a driving shaft, a driven shaft the axis of which is a prolongation of that of the driving shaft and one end of which faces and is adjacent to an end of the driving shaft, a driving bevel-wheel and clutch-member fast on the driving shaft, a driven bevel-wheel fast on the driven shaft, a transverse axially shiftable bevel-wheel, a clutch-member mounted on the driven shaft between the driving wheel and driven wheel and shiftable axially to and from the clutch-member of the driving wheel, and shifting mechanism connected both to said shiftable clutch-member and to the transverse bevel-wheel and operative to shift them simultaneously as described. 85

3. In driving and reversing mechanism the combination of a driving bevel-wheel, a driven bevel-wheel, a clutch-member included in one of said wheels, a transverse axially movable bevel-wheel, a shiftable clutch-member adjacent to the wheel which includes the aforesaid clutch-member, shifting mechanism connected both to said shiftable clutch-member and to the transverse bevel-wheel and operative to shift them simultaneously, and a spring that normally presses the clutch-members together and acts through the shifting mechanism on the transverse bevel-wheel to keep it disengaged from the other wheels. 100

4. In driving and reversing mechanism the combination of a driving bevel-wheel and clutch-member, a driven bevel-wheel, a transverse axially movable bevel-wheel, a shiftable clutch-member, shifting mechanism connected both to said shiftable clutch-member and to the transverse bevel-wheel and operative to shift them simultaneously, and a spring that normally presses the clutch-members together and acts through the shifting mechanism on the transverse bevel-wheel to keep it disengaged from the other wheels. 110

5. In driving and reversing mechanism the combination of a driving bevel-wheel and clutch-member, a driven bevel-wheel, a transverse axially movable bevel-wheel, a shiftable clutch-member, and shifting-mechanism comprising a lever connected to the shiftable clutch-member, another lever connected to the transverse bevel-wheel, and a third lever movable by hand and operative on both of the others simultaneously. 120

6. In driving and reversing mechanism the combination of a driving bevel-wheel and clutch-member, a driven bevel-wheel, a transverse axially movable bevel-wheel, a shiftable clutch-member, and shifting-mechanism comprising a lever connected to the shiftable clutch-member and having a slot- 130

ted arm, another lever connected to the transverse bevel-wheel and having a slotted arm, and a third lever movable by hand and engaged with the slotted arms of the other levers.

- 5 7. In driving and reversing mechanism the combination with two levers having parallel pivotal axes and connected with shiftable parts of the mechanism and each having a slotted arm, of a third lever movable by hand and engaged with the slotted arms of the other levers, its pivotal axis being in a plane that cuts the pivotal axes of the other levers at right angles.
- 10 8. In driving and reversing mechanism the combination with two levers having parallel pivotal axes and connected with shift-

able parts of the mechanism of a third lever movable by hand and operative on both of the others simultaneously, its pivotal axis 20 being in a plane that cuts the pivotal axes of the other levers at right angles.

9. In driving and reversing mechanism the combination with two levers having vertical pivotal axes and connected with shift- 25 able parts of the mechanism, of a third lever having a horizontal pivotal axis and movable by hand and operative on both of the others simultaneously.

DANIEL L. DODGE.
THOMAS F. ARMSTRONG.
